[57] CLAIM

The ornamental design for a foldable frame for a soccer goal, as shown and described.

DESCRIPTION

FIG. 1 is a front elevation view of a foldable frame for a soccer goal showing our new design;
FIG. 2 is a top plan view thereof;
FIG. 3 is a left side elevation view thereof;
FIG. 4 is a right side elevation view thereof;
FIG. 5 is a rear elevation view thereof;
FIG. 6 is a bottom plan view thereof; and,
FIG. 7 is a perspective view thereof.

The broken lines showing of the net is for illustrative purposes only and forms no part of the claimed design.
